UNITED STATES PATENT OFFICE.

WILFRID E. DIEGEL, OF RIVER ROUGE, MICHIGAN.

GAME.

Application filed August 5, 1925. Serial No. 48,187.

To all whom it may concern:

Be it known that WILFRID E. DIEGEL, a citizen of the United States, residing at River Rouge, in the county of Wayne and State of Michigan, has invented certain new and useful Improvements in Games, of which the following is a specification.

This invention is a game involving the use of a rotatable wheel set within a base, 10 sections of the wheel and surrounding base being diametrically aligned with each other; and these sections being then painted or colored with the same colors but in diverse order, so that upon twirling the wheel and 15 its coming to rest, only a comparatively few of the said aligned wheel and base sections will be found to match in color. Numbered counters are also used in conjunction with the colored wheel and base; and the object 20 of the game is to provide an attractive and entertaining form of indoor amusement.

In the drawing

Figure 1 is a plan view;

Figure 2 is a transverse vertical section;

Figure 3 is a detail of one of the counters.

This invention comprises a base 1, having a shallow, circular recess 2 formed in the center thereof. A pivot pin 3 is rigidly mounted at the exact center of the recess 2, and a solid disc or wheel 4 is provided with a central sleeve 5 adapted to freely and snugly engage the pin 3, whereby the wheel is adapted to rotate upon the pin as the axis. The upper face of the wheel is 30 intended to fall in the same horizontal plane with the upper face of the base, and the base is provided with a raised border 6 to prevent counters from falling off. The upper surface of the wheel and base are divided into 35 a plurality of diametrically or radially aligned sections 7-8. These sections are angularly co-equal, and the sections of the wheel and of the base are colored with the same colors, but in diverse order, or rather 40 with no particular order at all, and so that upon the wheel coming to rest after rotation, only a relatively few of the said aligned sections will be found to match in point of color. In other words, the sections of the 45 wheel are differentiated from each other by each section being colored with an individual color, and the sections of the base are differentiated with the same colors as used upon the wheel sections, but the order of coloring 50

of the sections of the wheel does not follow the order of coloring of the base sections. For instance, in the drawing the sections of the wheel are colored in sequence, purple, orange, green, white, blue, yellow, brown, red, passing around the wheel in a clockwise direction; while the sections of the base are colored in sequence, blue, orange, purple, white, brown, red, green, yellow. In this combination of colors it will be seen that it is possible to match not more than two color sections of the wheel with corresponding color sections of the base. As here shown these color sections are brown and red. But any other arrangement of the color sections may be employed, as may be desired, so that there is no general matching of all of the color sections. While the names of the colors are shown on the drawing, this is merely for indicating a certain set of colors, and when the games are made for the market, the colors themselves should be employed in painting up the games, and the names should be omitted. The wheel 4 is provided with two studs 9 as a convenience for twirling the wheel. Register marks 10 in the form of arrow-heads are printed at the peripheral centers of the color sections of the wheel 4. Nine counters 11 are provided, the same being numbered seriatim 1 to 9 inclusive.

One method of using the described apparatus in play is as follows:

Each player plays in turn, and places the counters numbered 1 to 8 upon the colored sections of the base 1, one counter upon each section. The player then twirls the wheel 4 and upon its coming to rest, he notes the color sections of the wheel that match with those of the base, and adds together the numbers on the counters found upon those sections. To be properly matched, the arrow-heads upon the wheel sections must fall within the lines of the base sections which demarcate the several colors. After a player counts his first hundred points, he is then entitled to use the counter numbered 9 instead of the one numbered 1, whereby his progress is accelerated.

While I have herein described a certain specific manner and method of constructing and assembling the elements of my invention, it is understood that I may vary from the same in minor details, not departing from the spirit of my invention, so as best

to construct a practical device for the purpose intended, as defined in the appended claims.

I claim:

- 5 1. A game comprising a base having a central circular recess; a disc wheel rotatably mounted within the recess, the upper surfaces of the wheel and base falling in the same plane and being divided into a plurality of radially aligned sections, the said section of the wheel and base being colored, and individually distinguished, by like colors, but arranged in diverse order as between the wheel and base.
- 15 2. A game comprising a base having a

central circular recess; a disc wheel rotatably mounted within the recess, the upper surfaces of the wheel and base falling in the same plane and being divided into a plurality of radially aligned sections, the said section of the wheel and base being colored, and individually distinguished, by like colors, but arranged in diverse order as between the wheel and base; a plurality of counters numbered seriatim and adapted for positioning upon the color sections of the base.

In testimony whereof I affix my signature.

WILFRID E. DIEGEL.
